6 Claims. (Cl. 53—41)

The present invention relates to fibre slip cover containers, and more particularly to such containers which are constructed in a manner which permits them to be transported from their place of manufacture to a filling station with their covers removably attached to them and with one end open, ready to be filled with a product.

One type of container which has long been in use is the so-called fibre salt can which comprises an unflanged tubular body having both of its ends closed by means of fibrous slip covers which are glued in place thereon. Heretofore, these cans have been used almost exclusively for the packaging of salt and have been shipped by the manufacturer to the packer with both ends permanently glued in place, the filling of the salt into the container being done through a small hole which is cut in the top slip cover.

Recently, however, such containers have been used in the packaging of non-flowable bulky goods such as stockings, lingerie, etc. In such packages, the top slip cover is imperforate, and the goods must be filled through an open end of the container. As a result, the containers must be shipped by the manufacturer to the packer with one of their ends unsealed. The usual practice in such case would be to ship the unsecured slip covers separately from the container. However, this method of shipment has certain drawbacks which are inherent in it because of the nature of the slip covers, which are drawn from flat sheet stock and formed with single thickness peripheral flanges which are flimsy and easily distortable until they are glued in place on the container body, which thereafter supports them. As a result, the slip covers are easily damaged when shipped separately from the cartons in unnested relationship. If they are shipped in nested relationship in stacks, the slip covers have a tendency to become wedged together and cannot be easily separated.

The present invention contemplates the elimination of these drawbacks by providing a container construction wherein a top slip cover is temporarily secured in place on the bottom end of the container which it will eventually seal. To permit this, the top slip cover is made larger in diameter than the bottom slip cover and is telescoped over the bottom slip cover after the latter has been permanently assembled to the container but prior to shipment of the container to the packer.

In order to stiffen the flange of the telescoped slip cover and to cause it to shrink into tight frictional contact with the bottom slip cover, it is subjected to a heating operation after it has been positioned on the bottom of the container.

After the top slip cover has thus been temporarily secured in place on the bottom end of the container, the rigid bottom end assembly provides a solid base for it and consequently there is little or no chance that the top slip cover will become damaged or will fall off during the time it is shipped to the packer and is conveyed in his runways. As a result, the packer is virtually assured of receiving a top slip cover with each container and of having it remain with the container during its handling prior to and during filling operation. In addition, since the container is shipped with its top end open, the packer need not remove the top slip cover prior to filling the container, but can defer this operation until he is ready to glue the top slip cover per-

2

manently onto the container. This is especially advantageous in packing lines where the gluing station is removed from the filling station.

An object of the invention therefore is the provision of a method of handling a fibrous slip cover container wherein the top slip cover is carried on the bottom end of the container during shipment, storage and/or filling in such manner as to insure that it remain thereon until the packer is ready to permanently secure it to the open mouth of the container.

Another object is the provision of a container construction which makes it possible to practice the instant method invention.

Numerous other objects and advantages of the invention will be apparent as it is better understood from the following description, which, taken in connection with the accompanying drawings, discloses a preferred embodiment thereof.

Referring to the drawings:

FIGURE 1 is a perspective view of the container of the instant invention after it has been filled and finally sealed;

FIG. 2 is a vertical section taken substantially along the line 2—2 in FIG. 1;

FIG. 3 is a view similar to FIG. 2 but showing the container with its top end temporarily secured in place over the bottom end, preparatory to shipment from its place of manufacture, and

FIGS. 4 through 8 illustrate successive steps of the instant method invention.

As a preferred and exemplary embodiment of the instant invention, FIGS. 1 to 3 of the drawings disclose a novel container 10 which is specially designed to permit the practice of the method steps of the invention. As disclosed in these figures, the container 10 comprises a tubular body 12 which is preferably cylindrical in cross-section but which can be of any suitable cross-sectional shape. The bottom marginal end portion 14 of the body 12 is inwardly offset from the normal contour of the body in order to receive a drawn bottom slip cover 16 which preferably is formed from suitable fibre sheet stock and is formed with an imperforate flat central panel 18 and an annular peripheral flange 20 which extends at right angles to the panel 18. The inside surface of the slip cover flange 20 and the outside surface of the necked-in bottom marginal end portion 14 of the body are disposed in substantially face to face engagement and are permanently joined together by a suitable adhesive (not shown) which is interposed between them.

The upper marginal end portion 22 of the body 12 is also necked-in, but somewhat more shallowly than is the bottom marginal end portion 14, the difference in depth of offset between these two portions being equal to the thickness of the bottom slip cover flange 20 so that the diameter of the outer surface of the flange 20 is substantially equal to the diameter of the outer surface of the necked-in body portion 22.

The container 10 also comprises a top slip cover 30 which is essentially similar in construction to but somewhat larger in diameter than the bottom slip cover 16, being provided with a central imperforate panel 32 and right angled annular peripheral flange 34. The inside diameter of the flange 34 is about equal to or slightly larger than the outside diameter of the bottom slip cover flange 20 and the upper necked-in body portion 22, so that the top slip cover 22 can be telescoped onto either end of the container 10 after the bottom slip cover 16 is permanently secured in place. To finally seal the container 10, the top slip cover 30 is glued onto the top end of the container body 12, as seen in FIG. 2. However, since the container 10 must be filled with a bulky product 38, which may comprise an article made of a textile, the top

slip cover 30 cannot be glued in place on the body 12 at its place of manufacture, but must be transported in unglued condition to the place at which the filling operation takes place.

In many instances, as where the container 10 is manufactured by a container manufacturer, the empty unsealed container must be shipped and transported to the packers' plant for filling. Such transportation may necessitate the over-the-road shipment of such container by truck or rail and usually also includes a preliminary handling in conveyor runways in the packers' plant in order to convey it to the filling station. In other instances, as where the container is manufactured adjacent the packers' plant, over-the-road shipment is not necessary but the empty containers must still be transported to the filling station by conveyor.

Frequently, after the container has been filled, the top slip cover 30 is manually placed in position over the open mouth of the container to seal it, this sealing operation usually taking place at a separate sealing station. To facilitate this sealing operation, it is desirable that the top slip cover 30 be immediately available to the sealing operator. The method steps of the instant invention, which will now be described, provide a most convenient manner of fulfilling this requirement by making it possible to firmly but detachably secure the top slip cover 30 to the bottom end of the container during the time the container is being transported and filled, and by insuring that the top slip cover remain thus secured in position up until the time the filled container reaches the sealing operator, who needs only detach the top slip cover from the bottom end of the container and slip it onto the upper end of the container to which glue has previously been applied.

As a preparatory step of the method invention, the bottom slip cover 16 is glued in place on the necked-in bottom marginal portion 14 of the body 12 in order to provide a partially formed container having a closed bottom end. Next, the top slip cover 30 is positioned outwardly of the closed bottom end of the container, as seen in FIG. 4, and is then pressed into telescoping relationship over the permanently secured bottom slip cover 16. This step is made possible by the fact that the top slip cover 30 is of larger diameter than the bottom slip cover 16.

In theory, the slip cover flanges 22 and 14 could be so dimensioned as to create a snug fit between them which would provide sufficient frictional engagement to retain the top slip cover 30 in place on the closed bottom end of the container until it is intentionally removed therefrom by the sealing operator. However, in actual practice such a snug fit cannot be consistently obtained because of the fact that the drawn flange 34 of the top slip cover 30 has an inherent tendency to flare out and resume its original flat shape. This results in a loosening of its grip on the flange 20 and a consequent falling off of the top slip cover 30 from the bottom end of the container.

To prevent this, after the top slip cover 30 had been telescoped over the bottom slip cover 16, it is subjected to a shrinking operation which drives the moisture from the fibrous stock of the flange 34 and actually causes the flange 34 to contract diametrically into pressured engagement against the flange 14 and to thus greatly enhance the frictional engagement between the top and bottom slip covers 30 and 16. This shrinking engagement also has the effect of setting the fibres in the flange 34, and inhibits its tendency to return to its original flat state, thus substantially eliminating the inadvertent detachment of the top slip cover 30 from the bottom end of the container.

The shrinking operation is preferably effected by inserting the bottom end of the container, after the top slip cover 30 has been properly positioned thereon, into an annular metal shrinking ring 40 which is maintained in a heated condition by any suitable means. In the instant disclosure, as seen in FIG. 5, the heat is applied by an open flame 42 which emanates from an annular gas burner 44. The ring 40 is preferably provided with a tapered mouth

46 to readily receive the bottom end of the container. The interior portion 48 of the ring 40, however, is preferably cylindrical and is so dimensioned that it presses the flange 34 of the top slip cover 30 into intimate face-to-face contact with the flange 14 during the time it is being heated in order to reshape the flange 34, if it has already become distorted, and to insure face-to-face contact between the flanges 34 and 14. The application of heat to the flange 34 drives out a good part of the moisture in its fibres and causes it to contract and to shrink into tight, pressured engagement upon the flange 20. As soon as this has been accomplished, the container is removed from the shrinking ring 40 and is thereafter transported to the filling station. During this transportation, which as previously stated may include over-the-road shipment as well as in-plant shipment, the top end member 30 remains securely in position on the bottom end of the container. FIG. 3 illustrates the position of the container components during such transportation. It will be noted that in this stage, the outer surface of the flange 34 is substantially flush with the outer surface of the body 12. This is desirable because it lessens the possibility of having the raw edge of the flange 34 catch upon some other article, thereby causing detachment of the top slip cover 30, and is made possible by the fact that the depth of offset of the necked-in portion 14 is substantially equal to the combined thicknesses of the slip cover flanges 20, 34.

At the filling station, the product 38 is inserted into the container 10 through its open top end, as seen in FIG. 6. During this filling operation, the top slip cover 30 remains in non-interfering position on the bottom end of the container, as shown in FIG. 6, and requires no attention from the filling operator.

After the filling operation has been completed, the necked-in top marginal end portion 22 of the container body 12 is covered with a film of an adhesive or glue 50 which is preferably applied by a small adhesive applying roller 52 as seen in FIG. 7. Concurrently the top slip cover 30 is removed from the bottom end of the container, as is also illustrated in FIG. 7. Such removal is made possible by the fact that the previously described shrinking operation, although resulting in a secure frictional grip of the top slip cover 30 around the bottom slip cover 16, does not permanently secure the top slip cover 30 in place on the container but merely secures it firmly enough to prevent its inadvertent removal. Thus, when a straight longitudinal force is intentionally applied to the top slip cover 30, it slides along the bottom slip cover flange 20 and becomes detached from the container.

After the top slip cover 30 has thus been removed from the bottom end of the container, it is telescoped over the necked-in upper marginal edge portion 22 of the body 12 (see FIG. 8) and is permanently secured in place thereon upon the setting of the adhesive 50, after which the filled container 12 is ready for shipment through normal trade channels to the ultimate consumer. FIGS. 1 and 2 illustrate the filled container after the final sealing step has been accomplished. In this stage, the outer surface of the flange 34 is flush with the outer surface of the body 12, while the flange 20 is recessed a distance which is equal to the thickness of the flange 34.

It will be understood that the outer surface of the body 12 may be covered with a suitable label (not shown) which may either be printed directly on the body 12 or may take the form of a separate label sheet (not shown) which is adhesively secured to the outside surface of the container and which may overlap and be secured to all or a part of the slip cover flanges 20, 34. If the label is thus overlapped, the fact that neither of the flanges 20, 34 extends outwardly beyond the surface of the body 12 enhances the finished appearance of the container 12. However, it will be clear that the invention may still be practiced even if both marginal end portions of the body 12 are not necked-in, the main requirement being that the outside diameter of the bottom slip cover flange 20 be equal to the outside diameter of the upper marginal end

portion of the container so that the top slip cover 30 will fit onto both the bottom and the top ends of the container.

It is thought that the invention and many of its attendant advantages will be understood from the foregoing description, and it will be apparent that various changes may be made in the form, construction and arrangement of the parts and that changes may be made in the steps of the method described and their order of accomplishment without departing from the spirit and scope of the invention or sacrificing all of its material advantages, the form hereinbefore described being merely a preferred embodiment thereof.

I claim:

1. A container comprising a tubular body having a top and a bottom marginal end portion, the diametral dimensions of said bottom marginal end portion being smaller than those of said top marginal end portion, a fibrous bottom slip cover having a peripheral flange which snugly engages around and is permanently secured to said bottom marginal end portion of said body, said flange having external diametral dimensions substantially the same as those of said top marginal end portion, and a fibrous top slip cover with a peripheral flange having its internal diametral dimensions substantially the same as the internal diametral dimensions of both said top marginal end portion and said flange of the bottom slip cover and detachably engageable around the flange of said bottom slip cover to retain said top slip cover in place on the bottom of said container prior to the filling of said container with a product.

2. The container of claim 1 wherein said bottom slip cover is permanently glued to the bottom marginal end portion of said body and wherein said top slip cover is shrunk into place on said bottom slip cover.

3. The container of claim 2 wherein both the top and the bottom marginal end portions of said body are necked-in to accommodate said slip covers, the bottom marginal end portion being necked-in to a depth greater than that of said top marginal end portion by a distance which is equal to the thickness of the flange of said bottom slip cover.

4. The method of handling tubular containers having fibrous top and bottom slip covers provided with flanges of different diametral dimensions, said dimensions internally of said top cover being substantially the same as those externally of said bottom cover, which comprises permanently securing a flanged fibrous bottom slip cover onto the bottom marginal end portion of a container body, placing a flanged fibrous top slip cover telescopically over said bottom slip cover with the flange of said top slip cover in frictional engagement with the flange of said bottom slip cover to detachably secure said top slip cover in place, and transporting said container with its top slip cover thus secured and with its top end uncovered preparatory to filling said container with a product.

15 5. The method of claim 4 with the additional step of shrinking the top slip cover into position onto the bottom slip cover in order to intensify the frictional engagement between said slip covers during shipment.

20 6. The method of handling tubular containers having fibrous top and bottom slip covers provided with flanges of different diametral dimensions, said dimensions internally of said top cover being substantially the same as those externally of said bottom cover, which comprises permanently glueing a flanged fibrous bottom slip cover onto the bottom marginal end portion of a container body, placing a flanged fibrous top slip cover telescopically over said bottom slip cover, heat-shrinking said top slip cover onto said bottom slip cover in order to create a strong temporary frictional engagement between said slip covers, transporting said container with its top slip cover thus secured and with its top end uncovered to a filling station, filling said container with a product, removing said top slip cover from the bottom of said container, and glueing said top slip cover into place on the top end of said body to seal said container.
